(Cl. D6—2)

To all whom it may concern:

Be it known that I, Garald A. Dohm, a citizen of the United States, residing at Dearborn, in the county of Wayne and State of Michigan, have invented a new, original, and ornamental Design for an Album, of which the following is a specification, reference being had to the accompanying drawings, forming part thereof, and wherein:

showing the album in opened position and respectively with and without the inner partition and binder.

The picture disclosed in Fig. 1 is conventional and represents no particular individual.

The background of the design, partially disclosed in Figs. 1 and 3, is continued as the background of the rest of the design.

The back of the album is unornamented.

I claim:
